Application October 28, 1944, Serial No. 562,028
In Great Britain July 15, 1943

9 Claims. (Cl. 35—25)

1

This invention relates to improvements in training devices for use with gun-sight apparatus and has for its principal object the provision of improved means for enabling an instructor to check the manner in which a gunner undergoing instruction is controlling such apparatus. In aiming at his target (which is generally a moving one) the gunner should keep a line of sight defined by optical parts of the sighting apparatus aligned on the said target and, as a rule, he must also keep a range setting device in correct adjustment. When a gunner is undergoing training with such apparatus it is usual for an instructor to provide a moving dummy target, such as a model of an aircraft, or an image of a target projected on a cinematograph screen. Hitherto there has been no simple method by which an instructor can check the accuracy of a gunner's control of the direction of a line of sight, or the adjustment of range setting apparatus during such training. The present invention provides a device that enables an instructor to carry out such checks and, as a subsidiary feature, means for checking the gunner's fire control may also be provided.

The need for such checks is particularly great in training with computing gun-sights of the type in which an optical sighting system is mounted to partake in the angular movement of the gun for which corrections are to be computed and in which a correction is automatically calculated by the computing mechanism on the basis of the angular rate of movement of the gun and is so applied as to displace the line of sight from the line of the gun through an angle equal to the correction angle to be imparted to the said gun. Such sighting systems are known as disturbed-sight systems, and, in using them, bad operation of the controls may lead to considerable errors, as a result of the reaction of the gun velocity on the line of sight through the computing mechanism; it is therefore highly desirable to ensure that an instructor shall be able to check the degree of accuracy of the control of the sight executed by the gunner.

The present invention provides means whereby an instructor can maintain a continuous check on a gunner's operation of the apparatus during training. According to the invention, an optical light projector is so associated with the sighting apparatus that a beam of light can be projected on to a dummy target, or a projected image of a target, towards which the line of sight is directed, the projector being coupled with the sighting apparatus in such a manner that the axis of the

2

beam follows the movements of the line of sight. Furthermore, in a preferred form of the invention as applied to a sight in which range is determined by matching the apparent diameter of the target as seen by the gunner with an adjustable frame or system of spaced markings, which is adjusted by the gunner to have the same apparent diameter as the target, means are provided to vary the diameter of the projected beam and these means are connected to the range-setting adjustment of the sight in such a way that the diameter of the beam at a given distance from the projector is made proportional to the apparent diameter of the adjustable frame. Seeing that the target employed is not usually circular (it might, for example, be a moving model or a moving image of an aeroplane) the expression "apparent diameter of the target" must be understood to include the diameter of an imaginary circle framing the whole or a part of the target across a known dimension thereof (e. g. across the wing span of the hypothetical aeroplane aforesaid).

Preferably also means are incorporated to mask from the gunner's vision, during the aiming operation, both the beam and the light spot that it projects on to the target.

There will now be given, with reference to the accompanying drawings, a description of one convenient construction of a device in accordance with the invention and illustrative thereof. It is however clearly to be understood that the illustrated device has been selected for description, merely by way of exemplification of the invention, and not in limitation thereof.

Fig. 1 is a side elevation of the device mounted on the optic head of a computing gun sight and some internal parts of the optic head are shown;

Fig. 2 is a plan view;

Fig. 3 is a horizontal axial section through the projector device, showing its internal construction and drawn to a larger scale than Figs. 1 and 2;

Fig. 4 is a wiring diagram for a fire control indicating arrangement; and

Fig. 5 is a schematic showing of the apparatus mounted on a standard gun mounting, and illustrating the manner of use of the visible sighting indicia.

Fig. 1 illustrates the invention as applied to a computing gun-sight of the type described in allowed U. S. application No. 358,382, allowed July 6, 1945. This sight comprises computing mechanism carried in a base secured to the gun or guns with which the sight is intended to be used, and

an optic head rotatably mounted thereon. The optic head contains the optical parts of the sighting apparatus that define the direction in which the sight is aligned, i. e., defines the line of sight that the gunner has to keep on a target in aiming the gun. Reference 10, in Fig. 1, denotes generally the optic head, which is fixedly mounted on data transmission casing 38 rotatable about the normally vertical axis X—X with respect to the base of the apparatus as shown in Fig. 5. The latter is secured to the gun or guns with which it is intended to be used and therefore partakes in the elevational movements of the gun or guns with respect to the turret in which it, or they, is, or are mounted. In other words, the sight turns in azimuth with the gun. The computing mechanism, carried in the base of the sight, is operated by the rate of turn of the gun or gun-turret in azimuth to compute a correction which is applied to turn the optic head 10 of the sighting apparatus about the axis X—X through an angle related, in the manner described in the aforementioned U. S. application No. 358,382, to the azimuth correction to be imparted to the gun.

As illustrated in Fig. 5, the training device assembly comprises an optic head 10, mounted on a machine gun data transmission casing 38, which is secured, in the usual manner, on machine gun 60, having a barrel 61, and supported on a mount, indicated generally at 62. A screen, 70, is set up at a suitable distance from the machine gun mount, and will support a model target 71, or a projected image thereof. The student gunner's line of sight to the target is indicated generally by 72, while the instructor's separate line of sight is indicated by 73. A special projector 11, mounted on the optic head 10, is arranged to project a beam 74 of colored light, which beam forms a light spot 75 on the screen. This light spot is of any suitable color, such as red, and is masked from the view of the gunner by being neutralized by a complementary filter of green, so that he sees only the target 71 and not the light spot 75. The optical axes of the machine gun barrel, the optic head, and the beam projector are mounted for simultaneous parallel operation, so that the several lines of sight and the light beam converge at the target, as will be described more in detail herein.

The optic head includes a light source 1, a range light gate 2, an inclined tilting mirror 3, a lens 4, an inclined reflecting plate glass window 5 and a color filter 6, which may, for instance, be a green glass filter. Light emanating from the source 1 passes through the range light gate 2, which has a horizontal and a vertical cross-line (not shown) and is capable of adjustment for target dimensions and range as described in the aforesaid U. S. application. This light then impinges on the mirror 3, which is fixed to a rocking member 21 pivoted at 21' for movement about a horizontal axis perpendicular to the direction of incidence of the light. The mirror 3 is normally positioned at an angle of 45° with respect to the incident light. After reflection upwards by this mirror, the light passes through the collimating lens 4 and impinges, in a substantially parallel beam, on the inclined window 5, from which it is reflected to the gunner's eye. The lens produces a virtual image of the range light gate 2 at a long distance from the lens (infinite if the lens is adjusted to produce a truly parallel beam) and, as the gunner views this image in the reflecting window 5, it appears to him to lie in the general di-

rection of the target, 11, which he is viewing through the said window. In directing the line of sight, 72, on the target the gunner aligns the point of intersection of the cross-lines of the image of the range light gate 2 (which constitutes the foresight of the sighting apparatus) on the target as seen by him through the window 5 (which constitutes the back sight). The mirror 3 is tilted by the computer (through the agency of the member 21, which includes a toothed sector meshing with a driving pinion 58) so as to apply the elevational correction that it calculates to the line of sight; this alters the direction of the line of sight leading from the window to the image of the cross-lines of the range light gate.

The device of the present invention comprises an optical light projector the case 11 of which is mounted on a pair of pivots 12 (Figs. 1 and 2) for movement in a vertical plane about a horizontal axis. The pivots 12 are screwed adjustably into the opposite limbs of a forked bearing bracket 12' which, in turn, is adjustably fixed on the top of the case of the optic head 10. The purpose of this projector is to throw a beam of light, 74, substantially in the same direction as the line of sight. Within the projector case 11 is housed a lamp 13 (Fig. 3) carried in an adjustably mounted lamp holder 13' and the optical projecting system comprises a condenser lens 14, an iris diaphragm unit 15, a projector lens 16 and a color filter 17, which might be mounted in the vicinity of the projector lens instead of being adjacent the condenser lens, as shown.

It is the purpose of the filter 17 to impart to the projected light beam a color to which the filter 6 in the optic head is opaque. Thus, in conjunction with a green glass filter 6, a red glass filter 17 would be appropriate.

The iris diaphragm unit 15 is of a conventional type, its leaves being movable by means of a lever 15' and a spring 15'', acting on this lever, tends to keep the stop at maximum aperture. The manner in which the aperture is varied, in accordance with the setting of the range light gate 2 will appear hereinafter.

The movement of the projector about its horizontal axis (pivots 12) is made to correspond with the movement of the mirror 3 about its axis of rotation. For this purpose a link 18 (Fig. 1) is pivotally connected at 18 to the projector case 11 and is also pivotally connected at 18' to a short eyebolt 20 which, in turn, is secured to one end of a lever 21 by nuts 20' manipulation of which permits the free length of said eyebolt to be adjusted. Lever 21 is pivoted centrally, at 21', for movement in a normally vertical plane and it carries, at its other end, a roller 22 resting on a plate 23 on the upper end of a push rod 24, slidably in a sleeve 25 fixed in the casing of the optic head. The lower end of the push rod 24 rests on a roller 26 carried by the tilting member 27, controlled by the computer mechanism and rigidly supporting the mirror 3 as hereinbefore explained. The centre of gravity of the projector is located at a point forward of its pivotal axis, so that under all operating conditions contact is maintained between the roller 22 and the plate 23.

The linkage is so arranged that the axis of the projector and the line of sight maintain a constant relationship. For this purpose, the said linkage is designed to ensure that the angular movement of projector case 11 about the axis of its pivots 12 is, for small angles of rotation, substantially one-half of the angular movement of the mirror 3, about its axis of rotation (pivots

27') and is in the opposite direction. The lever 18' of the iris diaphragm 15 is connected by a Bowden transmission 28 with the range light gate 2 and is adjusted so that the diameter of the iris produces a light-spot, 75, which just frames the target, 71, aimed at when the said target is accurately framed in the range light gate; moreover the design and arrangement are such that the diameter of the iris aperture is varied proportionately with variations in the apparent diameter of the range light gate. A stop bracket for the projector end of the Bowden casing is indicated at 31 and 29 is an adjuster nut.

To enable an instructor to check the gunner's fire control, by viewing the target along line of sight 18, the circuit of the projector lamp 13 may be arranged as shown in Fig. 4. A firing switch 32, fitted in the gun turret, is of the well-known press-to-break type and 33 is a resistance for regulating the voltage supplied to lamp 13. The lamp, the resistance and the firing switch are connected in series across the current supply terminals 34 but the firing switch is shunted by a flasher switch 35 which may comprise a mechanical make-and-break (indicated by cam 36) and may be driven continuously from the drive motor gear train of the gun. It will be seen that, with this arrangement, although the flasher switch is in continuous operation, it can be effective to flicker the projector light only when the shunt circuit through the firing switch is opened, by reason of the gunner depressing the said firing switch. When the gunner is not firing, that is to say, when he is not depressing the switch 32, the latter stays closed and short circuits the flasher 35, so that the light from the projector lamp 13 remains steady. Thus the instructor has only to note whether or not the flicker, which denotes firing, takes place when the gun is correctly sighted and ranged, as indicated by the proper framing of the target 71 in the light-spot 75 produced by the projector.

In order to use the device for training purposes the following initial adjustments are made. The sight is turned until the image of the cross-lines coincides with a mark on a screen at the distance or mean distance at which the dummy target or target image is to be followed during training operations. The collimating lens 4 is then adjusted until there is no apparent shift of the image of the cross-lines relative to the mark if the gunner moves his head so as to look at the mark through a different part of the window 5. The lamp 13 is adjusted centrally with respect to the beam it produces and the projector lens 16 is adjusted and focussed for sharp definition of the light-spot 75 produced by the beam 14 impinging on the screen 10. The projector is then aligned by small adjustments of the bearing bracket 12' relatively to the top of the optic head 10 and also by fine adjustment of the length of the eyebolt 20, so that the cross-lines from the range light gate, when seen in the reflecting window 5, are centrally placed on the light-spot 75. The sight is then turned until a target is sighted, i. e., until the cross-lines of the image of the range light gate are centred upon the dummy or practice target, which may be an image 71 of an aircraft projected on to the screen. The iris diaphragm 15 is adjusted by effectively lengthening or shortening the wire of Bowden transmission 28 by manipulating the nut 29, until the light-spot just frames the target. The device is now adjusted for use.

For training purposes the sighting apparatus

fitted with the above-described device may be mounted in a gun-turret or dummy gun-turret, and a target may, as already intimated, be projected on to a cinematograph screen. During 5 operations by the gunner the computing mechanism turns the optic head 10 relatively to the base of the apparatus and also tilts the mirror 3 in a direction perpendicular to the said base, by computed amounts, thus applying continuously to the line of sight varying movements in two perpendicular planes. Since the projector is rigidly fixed to the optic head and the line of sight turns with the optic head, the projected beam receives the same movement, in the same direction relative to the base, as does the line of sight. Further, as previously explained, the linkage between mirror 3 and the projector moves the projector through an angle equal to half that moved through by the mirror and therefore equal to the angle moved through by the line of sight. The axis of the beam, therefore, moves in correspondence with the line of sight. The gunner tracks the target by keeping the line of sight aligned on it and ranges the target by keeping it framed in the range light gate. The projector projects on to the screen a light-spot which corresponds with the tracking and ranging of the gunner, and hence should be maintained centred on the target and framing it, as the size of the target image is varied in accordance with the apparent distance of the target from the gunner. The red and green filters in the path of the beam and in the gunner's field of vision, respectively, are complementary and neutralize each other, the effect being to prevent the gunner from seeing the light-spot and using it to follow the target instead of aiming by means of his line of sight. When the gunner considers that he is tracking and ranging accurately he depresses the firing switch and renders the flasher switch effective in the manner and for the purpose already explained.

We claim:

1. Apparatus for supervising gunnery practice wherein an optical gun-sight mechanism is aimed at a target, and the gunner sees an unmodified target in the gun-sight, the improved system for indicating the resulting aim to an instructor without knowledge of the gunner, comprising means operable by manipulation of the gun-sight mechanism to project a visual indication on the target in register with the line of sight of the gun sight, and separate means in the gun-sight mechanism for masking said visual indication from the gunner only.

2. Apparatus for supervising gunnery practice wherein a disturbed gun-sight mechanism having an optical sighting system is aimed at a target by a student gunner, comprising means operable by manipulation of the gun-sight mechanism to project a visual indication on the target in register with the line of sight of the gun sight and visible to an observer, and separate means in the optical system of the gun-sight for masking said visual indication from the gunner, the visual indication being variable in size and intensity by and with the range-finder of the gun-sight range-setting apparatus.

3. Apparatus for supervising gunnery practice wherein an optical gun-sight mechanism is aimed at a target, comprising means operable by manipulation of the gun-sight mechanism to project a beam of light and impose a visible light spot on the target in register with the line of sight of the gun sight, and separate optical

means in the gun sight for neutralizing the light spot and leave only the unmodified target visible to the gunner.

4. Apparatus for supervising gunnery practice wherein an optical gun-sight mechanism is aimed at a target, comprising means operable by manipulation of the gun-sight mechanism to impose a light spot on the target, co-diametral therewith, and in register with the line of sight of the gun sight, and separate optical means in the gun sight for neutralizing the light spot without affecting the visibility of the target to the gunner, whereby the gunner sees only the target, and an observer can observe the opposition of the light spot to and on the target and determine the accuracy of the gunner.

5. Apparatus for supervising gunnery practice wherein a gun-sight mechanism having an optical sighting system is aimed at a target, comprising means operable by manipulation of the gun-sight mechanism to impose a co-diametral light spot on the target and to intermittently register with the image viewed in the line of sight of the gun sight, and separate optical filter means in the gun sight for neutralizing the light spot without affecting the gunner's visibility of the target image.

6. Apparatus for supervising gunnery practice wherein a gun-sight mechanism having an optical sighting system is aimed at a target, comprising means operable by manipulation of the gun-sight mechanism to project a controlled colored visual indication on the target in register with the line of sight of the gun sight, and separate optical means in the gun sight comprising color filters for neutralizing said visual indication to render only the target visible to the gunner.

7. Apparatus for supervising gunnery practice wherein a gun-sight mechanism having an optical sighting system is aimed at a target, comprising means operable by manipulation of the gun-sight mechanism to project a colored visual indication on the target, in register with the line of sight of the gun-sight, means variable by and with the range-finder of the gun-sight range.

8. Apparatus to control the intensity of the projected visual indication, and separate means in the optical sighting system comprising complementary color filters for neutralizing said colored visual indication and render only the uncolored target visible to the gunner.

9. Apparatus for supervising gunnery practice wherein a gun-sight mechanism having an optical sighting system is aimed at a target by a gunner, comprising means operable by manipulation of the gun-sight mechanism to impose a red light spot on the target in register with the line of sight of the gun sight and green color filters in said optical sighting system effective to neutralize said red light spot so that the gunner sees only the original target.

10. Apparatus for supervising gunnery practice wherein a gun-sight mechanism having an optical sighting system is aimed at a target by a gunner, and an instructor visually checks the target to determine accuracy of the gunner's aim, comprising means operable by manipulation of the gun-sight mechanism to impose a colored light spot on the target in register with the line of sight of the gun-sight and complementary color filters in the optical sighting system for neutralizing said colored light spot so that the gunner is able to see only the original target, while the instructor is able to see both the original target and the colored light spot imposed thereon.
